UNITED STATES PATENT OFFICE.

RUDOLF E. WOODRICH, OF NEW YORK, AND CHARLES LANGBEIN, OF BROOKLYN, ASSIGNORS TO THE NORMAL LOCK MANUFACTURING COMPANY, OF NEW YORK, N. Y.

LOCK.

SPECIFICATION forming part of Letters Patent No. 309,181, dated December 9, 1884.

Application filed April 11, 1884. (No model.)

To all whom it may concern:

Be it known that we, RUDOLF E. WOODRICH, of the city, county, and State of New York, and CHARLES LANGBEIN, of Brooklyn, in the county of Kings and State of New York, have invented a new and Improved Lock, of which the following is a full, clear, and exact description.

The object of our invention is to provide a new and improved lock which can be secured and held in place without the use of screws, and which can be adjusted at different lengths, and can also be adjusted in such a manner that it cannot be unlocked from the outside.

The invention, which is an improvement on the lock for which Letters Patent No. 294,560 were issued to us on the 4th day of March, 1884, consists in the construction and arrangement of parts, as will be hereinafter fully described and claimed.

Reference is to be had to the accompanying drawings, forming part of this specification, in which similar letters of reference indicate corresponding parts in all the figures.

Figure 1 is a longitudinal sectional elevation of our improved lock, showing the bolt drawn within the casing. Fig. 2 is a longitudinal sectional elevation of the same, showing the bolt thrown out. Fig. 3 is a similar sectional view showing the plate locked in such a position that it cannot be opened from the outside. Fig. 4 is a cross-sectional elevation of the lock, showing the arrangement of the bolt, spindle, and key. Fig. 5 is a face view of the inner side of the neck for guiding the key. Fig. 6 is a side view of the same. Fig. 7 is an end view of the slotted barrel for receiving the key. Fig. 8 is a plan view of the guard in the neck for guiding the key. Fig. 9 is an inner face view of the guide-neck and the plug in the same.

The lock is constructed with a cylindrical casing, A, closed at the lower end and open at the upper end, over which casing a cylindrical cap, B, is held, which is provided with an aperture through which the sliding bolt C can pass. The cylindrical cap B is held in place by means of screws *a*, passed through the inner end of the said cap and through the

casing A, and by means of which screws the cap can be held on the casing in such a manner that the apertured end of the cap will be held a greater or less distance from the open end of the casing. There will be a series of holes in the casing arranged at certain distances apart for the screws *a* to engage to secure the cap in its adjustment on the said casing. By means of the cap the casing can be lengthened or shortened, as may be desired. The bolt C is provided at its base or inner end with an annular flange, C', between which and the apertured end piece of the cap B a spiral spring, D, is held, which surrounds the bolt and presses the same inward. The bolt is provided in its inner end with a screw-threaded aperture, E, into which a screw, F, is screwed, which is provided with a semispherical or like rounded head, F'. The lock-casing is provided in its lower end with a vertical slot, G, in the middle of which a partition, G', projects upward from the bottom of the casing, on which partition a cam-plate, H, is pivoted, which cam-plate is provided in its bottom edge with a groove, H', adapted to receive the partition or standard G'. The cam-plate is provided in its straight edge with a notch, h, into which a cross-screw, I, of the casing passes, as shown in Fig. 1, when the bolt is within the casing. The said cross-screw I limits and checks the movements of the cam plate or disk H when the same is raised or lowered, as shown in Figs. 1 and 2. A flat spring, J, is secured to the bottom of the casing at one end of the slot G, extends across the bottom of the slot, and has its end J' bent up in the shape of the letter S, which spring J rests against the cam-edge of the disk H at about the middle of the length of the horizontal part of the said spring. The casing A is provided in one side with a screw-threaded aperture, b, into which is screwed the externally-screw-threaded end of a sleeve, K, containing the knob-spindle L, on the outer end of which is the knob L'. The knob-spindle L is provided with an annular groove, l, for receiving the end of a screw, k, which is passed through the sleeve K, and serves to hold the said spindle in the sleeve in such a manner that the said spindle can re-

volve on its longitudinal axis, but cannot move in the direction of the length of the same. Around the aperture b an annular recess, e , is formed for receiving the end of a collar, M' , formed on and projecting from the inner end 5 of an escutcheon-plate, M , which collar M' is screw-threaded internally, and is screwed on the sleeve K at the inner end. The spindle L is provided at its inner end with two teeth, m , 10 which pass into corresponding apertures or notches in the side of the cam-plate H . On that side of the casing opposite the one in which the knob-spindle is held a recess, d , is formed for receiving the end of a neck, O . 15 In the middle of the recess d an aperture is formed for receiving the end of a locking-plug, P , held to revolve on its longitudinal axis in the middle of the neck O . The neck O is held 20 in place by the pin or screw I , which is screwed through the casing from the inside, so that its threaded end, after passing through the casing, passes into the inner end of the neck O , and holds the same on the casing, thus preventing burglars or others from removing the 25 neck O from the casing from the outside. The neck O is provided on its inner end with an annular flange or ridge, n , in which a recessed part, n' , is formed, the ridge being formed around the inner edge of the opening for the 30 plug P . The plug P is provided with a transverse slot, P' , extending from end to end, and the said plug is provided at its inner end with a short pin, o , which rests on the recessed part n' of the inner edge of the flange n . The plug 35 is also provided with a pin, R , which extends through the slot P' a greater or less distance from the inner end of the plug. The neck O is provided with a triangular or other shaped guard, S , which projects into the opening in 40 the neck and into a transverse slot in the plug P . The key T is provided at its inner end with a longitudinal notch, r , for receiving the transverse pin R in the plug, and is also provided in its side edges with notches s , for permitting the guard S to pass. The guard S can 45 be of different shapes and sizes for the different locks. The rounded edge of the cam-disk H is provided with an offset, t , against which the end of the S-shaped part J' of the spring 50 J rests when the bolt is in the casing, and said edge is also provided with an offset, w , against which the end of the part J' of the spring J can rest when the lock is adjusted in such a manner that the bolt cannot be withdrawn 55 from the outside.

The operation is as follows: The mortise is made in the edge of the door. The lock-casing A is placed in the mortise in such a manner that the outer end of the cap B is flush 60 with the edge of the door. Openings are made in the side surfaces of the door for receiving the knob-spindle and the neck O , the outer end plate, Q , of which neck must be flush with the outer surface of the door. The cap B is suitably adjusted on the casing, and the bolt C is 65 adjusted in such a manner that its outer end

will be flush with the end of the cap B when the bolt is withdrawn into the casing. The bolt is adjusted in length by turning the screw F in such a manner that it projects a greater 70 or less distance from the base end of the bolt. The tension of the spring D always remains the same, as the length between the inner surface of the top of the cap and the flange C' of the bolt is uniform, but the screw F projects 75 a greater distance from the inner end of the bolt when the bolt is lengthened than when the bolt is shortened. After the casing has been placed in the mortise in the door the inner end of the neck O is placed in the recess 80 d in the casing, and is held in place by the screw or pin I , the sleeve K is screwed into the opposite end of the casing on the inside of the door, and the escutcheon-plate M is screwed up against the surface of the door. 85 When the bolt is withdrawn, the cam-plate H is in the position shown in Fig. 1. If the cam-plate is turned in the direction of the arrow a' , Fig. 1, its edge acts on the rounded head F' of the screw F in the bolt, thus throwing the bolt outward, as shown in Fig. 2, in the same manner as the bolt is thrown by turning the spindle. It can be thrown by means 90 of the key T , which is introduced in the slotted plug P , and is provided at its inner 95 end with teeth u , which pass into notches in the cam-plate H . If the key is turned, the guard S passes through the slot or notch s in the key. If the lock is to be so adjusted from the inside that the bolt cannot be withdrawn 100 by means of the key, the cam-plate is thrown in the direction of the arrow a' until the end of the part J' of the spring J rests in the notch or offset w in the curved edge of the cam-plate; or, if the cam-plate H is in the position shown 105 in Fig. 2, it is turned back in the inverse direction of the arrow a' until the end of the part J' of the spring J rests in the notch w , as shown in Fig. 3. If the key is introduced when the cam-disk H is in the position shown in Fig. 2, 110 the guard S is in such a position that the prongs u of the key (shown in cross-section in Fig. 2) can pass the edge of the guard S , which is shown in dotted lines; but if the cam plate or disk H is turned in such 115 a manner that the end of the part J' of the spring J rests in the notch or offset w the notches p , formed in the side of the disk H for receiving the teeth of the key, will be in such a position that the guard S will be between 120 one of the said notches and the slot in the plug P —that is, if the plug P is turned in such a manner that its slot P' is in line with the two notches p , the guard S prevents the teeth of the key from passing into the said notches. 125 If the plug P is turned in such a manner that its slot will be in line with the edge of the guard S , so that the end of the key can pass the guard, then the teeth of the key will not be in line with the notches p , and thus cannot 130 be passed into the same; or, in other words, if the cam-disk H is adjusted in such a manner

that the part J' of the spring J rests against the offset or notch w of the cam-disk, the lock will be adjusted in such a manner that the key cannot be introduced effectively from the outside. By simply adjusting the cam-disk H the lock is made absolutely safe and burglar-proof, as it is impossible to change the position of the cam-disk from the outside without cutting out the door. The lock is held in place by the neck O and the sleeve of the knob-spindle, and is not screwed into the door. The lock must be secured in place from the inside of the door, and can only be removed from the inside, as the pin or screw I holds the neck O on the casing. By varying the position of the pin R in the slot P' of the plug P the lock will be changed to such an extent that the key of another lock cannot be used.

Instead of using only one guard, S , several guards can be used the same as in other locks.

Having thus described our invention, we claim as new and desire to secure by Letters Patent—

1. In a lock, the combination, with the casing A , of the adjustable cap B , the bolt C , having a flange, C' , at its lower end, the spring D , held between the said flange and the end of the cap, a screw screwed into the lower end of the bolt, and an operating-cam constructed to bear against the end of the bolt for throwing the bolt, substantially as herein shown and described.

2. The combination, with a lock-casing containing a bolt, of a cam-disk for acting on the bolt, a spindle projecting from one side of the casing and connected with one side of the cam-disk, and of a neck projecting from the opposite side of the lock-casing and provided with a revolving key-guide disconnected entirely from the bolt-operating mechanism, substantially as herein shown and described.

3. The combination, with a sliding bolt mounted in a casing having its outer key-hole provided with a guard, of an operating-cam pivoted in rear thereof, said cam being constructed with key-apertures on its opposite

sides and with offsets on its lower edge, substantially as shown, and a horizontal spring engaging the plain edge of the cam and provided with an upward-curved projection adapted to engage said offsets, whereby when the cam is arranged with one of its offsets engaged by the upward bent part of the spring it will be held from turning and its outer key aperture be held behind the guard, substantially as set forth.

4. In a lock, the combination, with the casing, of the sliding bolt, a pivoted cam-disk, a neck held to and projecting from one side of the casing, and a longitudinally-slotted plug or key-guide held to revolve in the said neck, which neck is held on the casing by a screw or pin, I , passed through the casing from the inside and extending into the said neck O , substantially as herein shown and described.

5. In a lock, the combination, with the casing, of a sliding bolt, a pivoted cam-disk having key-apertures in its inner and outer faces, a neck held to and projecting from one side of the casing, a slotted key-guide revolving in the said neck, and of a fixed guard held in the said neck at right angles to the longitudinal axis of the neck, and passing through a transverse notch in the plug, whereby the key is prevented from entering the apertures in the outer face of the cam when they have been turned behind the said guard by the inner mechanism, substantially as herein shown and described.

6. The combination, with a sliding bolt and its casing and operating-cam, of the spindle L , for operating said cam from the inner side, neck O , carrying the key-guard and guide, and the pin I , securing the neck to the casing from the inside, and also serving as a stop to limit the rotation of the cam, substantially as set forth.
